US0D1038057S

(12) **United States Design Patent** (10) **Patent No.:** **US D1,038,057 S**
(45) **Date of Patent:** **** Aug. 6, 2024**

(54) **MOBILE PHONE**

(71) Applicant: **Lenovo (Beijing) Limited**, Beijing
(CN)

(72) Inventors: **Conti Matias**, Beijing (CN); **Xiulan Zheng**, Beijing (CN)

(73) Assignee: **Lenovo (Beijing) Limited**, Beijing
(CN)

(**) Term: **15 Years**

(21) Appl. No.: **35/515,930**

(22) Filed: **Nov. 9, 2022**

(80) **Hague Agreement Data**

Int. Filing Date: **Nov. 9, 2022**

Int. Reg. No.: **DM/225679**

Int. Reg. Date: **Nov. 9, 2022**

Int. Reg. Pub. Date: **Dec. 30, 2022**

(30) **Foreign Application Priority Data**

May 9, 2022 (CN) 202230269874.2

(57) **CLAIM**

The ornamental design for a mobile phone, as shown and described.

DESCRIPTION

1.1 : Front

1.2 : Back

1.3 : Left

1.4 : Right

1.5 : Top

1.6 : Bottom

1.7 : Perspective

(Continued)

The broken lines shown in the drawings illustrate portions of the mobile phone and form no part of the claimed design. The dot-dash lines in the drawings define the boundaries of the claimed design and form no part thereof. The back surface of the mobile phone within the dot-dash lines forms part of the claimed design.

1 Claim, 7 Drawing Sheets
